FUEL TANK BOWL CONNECTION

Filed Dec. 22, 1945

UNITED STATES PATENT OFFICE

2,532,595

FUEL TANK BOWL CONNECTION

Albert H. Berger, Rocky River, Ohio, assignor, by
mesne assignments, to The Consolidated Iron-
Steel Manufacturing Company, Cleveland,
Ohio, a corporation of Ohio

Application December 22, 1945, Serial No. 636,625

3 Claims. (Cl. 285—211)

1

The invention relates to oil stoves, and more particularly to novel and improved liquid fuel supply means, including in combination a fuel supply and level maintaining bowl, a fuel supply pipe, and novel and improved connecting means between said bowl and said pipe.

An object of the invention is to provide a novel fuel retaining and supply device of the character indicated, of simple yet sturdy and leak-proof construction, which can be fabricated cheaply and easily, and assembled readily and rapidly, all parts being formed from widely available materials. Other objects and advantages will be apparent from a study of the following description in conjunction with the attached drawings in which:

Fig. 1 is a view in front elevation of a fragmentary portion of an oil stove embodying my invention;

Fig. 2 is a fragmentary top plan view of a portion of the bottom of a fuel supply bowl, taken on the line 2—2 of Fig. 1;

Fig. 3 is a sectional view taken on the line 3—3 of Fig. 2;

Fig. 4 is a sectional view taken on the line 4—4 of Fig. 3;

Fig. 5 is a perspective view of a thimble connector constituting one of the elements of this invention;

Fig. 6 is a view somewhat similar to Fig. 3 but showing a slightly modified form of the connection between the thimble and the supply pipe.

Before the present invention here illustrated is described in detail, it is to be understood that the invention here involved is not limited to the details of construction or the specific arrangement of parts herein illustrated or described, as the invention obviously may take various forms. It also is to be understood that the phraseology or terminology herein employed is for the purpose of description and not of limitation, the scope of the present invention being defined in the appended claims.

Speaking first generally, and with occasional reference to Fig. 1, I show a fragmentary portion of a stove 10 designed for liquid fuel consumption, such fuel being hereinafter identified by the term "oil." The stove may rest on any suitable support (not shown). The stove has a sheet metal frame including a top portion 12, a bottom portion 13, and an end portion 14. Oil is supplied from an inverted container 15 to an oil level bowl 16, by a valving arrangement involving a liquid level seal of known construction. It will be understood by those familiar with stoves of this type that the oil level in bowl 16 is automatically maintained at or near the line L.

The stove likewise comprises one or more burners 18, one being shown, said burners being in liquid communication with bowl 16 through the

2

oil supply pipe 19, and through connector devices 20 and 21. When the burner is in operation, the oil rises to the same level in the burner 18 as in bowl 16. The present invention is specifically directed to the structural relationship of bowl 16, fuel pipe 19 and the intermediate connector 21.

Connector 21 is a drawn metal member, here termed for convenience a thimble, having a generally cylindrical body portion and a closed end 22. This thimble body is sleeved or telescoped over the end of supply pipe 19 and may be secured thereto in any of several ways, a threaded connection being shown in Fig. 3. A wall portion of the thimble is flattened, at 23, for convenient seating against the outer face of the bottom wall 24 of bowl 16. I prefer to spot weld the thimble to the bowl bottom, after which a peripheral brazed connection is established around the line of contact of the edge of flat zone 23 with the bowl bottom as indicated at 26 in Fig. 4 and Fig. 3.

Liquid communication between bowl 16 and pipe 19 is established by piercing the bowl bottom and the thimble wall as at 27 in Fig. 3. It will be understood that the oil flows by gravity from bowl 16 towards burner 18, but such flow is controlled or terminated by manipulation of a valve knob 28 which operates a valve housed in connector 20, and not here specifically shown or described.

In prior constructions of this nature, the connecting and fuel transmitting means are either much more elaborate and expensive, or are not sturdy and dependable. Such prior connecting means are either expensive and cumbersome, or are neither leak-proof nor otherwise reliable. Connecting surfaces, in the past, were often soldered and were liable to separate under temperature fluctuations, so as to give rise to fire hazards through possible ignition of the leaking oil. The present construction is not only safely leak-proof, but it supports the bowl 16 and fuel container 15. The pipe 19 is secured to the bottom plate of the stove by one or more straps 30.

Fig. 6 shows a slightly modified form of thimble connection, in which the tubular thimble 21a is sleeved or telescoped with a sliding or forced fit over the pipe 19a, and the permanent connection is maintained by a brazing operation in an annular zone around the open end edge of the thimble, as indicated at 32.

What I claim is:

1. In an oil stove of the character described wherein said stove is provided with a fuel supply bowl having an exteriorly flat bottom and a fuel supply pipe in fuel flow communication therewith through the bottom, novel connection means for uniting said pipe and said bowl bottom comprising a drawn metal connector of generally thimble form having a hollow body portion sleeved over and permanently secured to the pipe

end, the side wall of the body portion having an external flat surface fitting and seated against the flat bottom of the bowl, said connector being spot welded to the bowl at one point, and brazed thereto over the entire area of the said flat surface, said connector and said bowl bottom being provided with aligned openings to permit liquid communication between said pipe and said bowl.

2. In an oil stove of the character described wherein said stove is provided with a fuel supply bowl having an exteriorly flat bottom and a fuel supply pipe in fuel flow communication therewith through the bottom, novel connection means for uniting said pipe and said bowl bottom comprising a drawn metal connector of generally thimble form having a hollow body portion sleeved over and permanently secured to the pipe end, the side wall of the body portion having an external flat surface fitting and seated against the flat bottom of the bowl, said connector being spot welded to the bowl at one point, and brazed thereto over the entire area of the said flat surface, said connector and said bowl bottom being provided with aligned openings to permit liquid communication between said pipe and said bowl, there being a brazed connection between said pipe end and said connector surrounding the external terminus of their zone of mutual contact.

3. In an oil stove of the character described wherein said stove is provided with a fuel supply bowl having an exteriorly flat bottom and a fuel supply pipe in fuel flow communication therewith through the bottom, novel connection means for uniting said pipe and said bowl bottom comprising a drawn metal connector of generally thimble form having a hollow body portion sleeved over and permanently secured to the pipe end, the side wall of the body portion having an external flat surface fitting and seated against the flat bottom of the bowl, said connector and said bowl bottom being provided with aligned openings to permit liquid communication between said pipe and said bowl.

15 ALBERT H. BERGER.
